GAMEBOARD

Eraldo Sansoni, Via Amendola 40, Conegliano Veneto,
Treviso, Italy

Filed Nov. 2, 1973, Ser. No. 412,465

Claims priority, application Italy May 11, 1973

Term of patent 14 years

Int. Cl. D21—01

U.S. Cl. D34—5 SS

FIG. 2

FIG. 1 is a perspective view of a gameboard in partially opened condition;

FIG. 2 is a perspective view of the gameboard in closed position, the two sides of the gameboard being identical in appearance; and

FIG. 3 is a rear elevational view of the gameboard in closed condition.

I claim:

The ornamental design for a gameboard, as shown and described.
